UNITED STATES PATENT OFFICE

119,191

DESIGN FOR A FIGURE OF A BIRD

George W. Vipond, Grand Rapids, Minn.

Application July 26, 1939, Serial No. 86,258

Term of patent 3½ years

To all whom it may concern:

Be it known that I, George W. Vipond, a citizen of the United States, residing at 1001 North Third Avenue West, Grand Rapids, in the county of Itasca and State of Minnesota, have invented a new, original, and ornamental Design for a Figure of a Bird, of which the following is a specification, reference being had to the accompanying drawing, forming part thereof.

Fig. 1 is a view in side elevation of a figure of a bird, showing my new design;

Fig. 2 is a view in front elevation thereof; and Fig. 3 is a top plan view.

The drawing is lined to indicate contrasting colors.

I claim:

The ornamental design for a figure of a bird, as shown and described.

GEORGE W. VIPOND.
